UNITED STATES PATENT OFFICE.

DEMETRIO MAGGIORA, OF PARIS, FRANCE.

GAS-GENERATOR.

1,255,765.

Specification of Letters Patent.

Patented Feb. 5, 1918.

Application filed July 5, 1916. Serial No. 107,596.

To all whom it may concern:

Be it known that I, DEMETRIO MAGGIORA, engineer, Italian subject, of 10 Rue du Quatre-Septembre, at Paris, Department of the Seine, France, have invented certain new and useful Improvements in Gas-Generators; and I do hereby declare the following to be a full, clear, and exact description of the invention, such as will enable others skilled in the art to which it appertains to make and use the same.

This invention relates to acetylene or other gas generators.

An attempt has been made in the generator according to the present invention to make use of a closure which, while being watertight, permits of a fresh charge of carbid being easily introduced.

To this end, the bell of the generator is provided with a well or tube in which a pocket filled with water, forming a liquid seal, and a perforated pocket in which the carbid may be placed, can be lodged by turns. After introducing the carbid into the latter, the system is displaced in such a way as to bring the pocket full of water opposite to the well, thus forming a hydraulic joint.

I will describe with reference to the accompanying drawing a construction in accordance with this invention but I do not limit myself to the precise construction described and illustrated.

Figure 1 is a plan of a generator according to the invention.

Fig. 2 is a vertical section on the line I—I—I—I of Fig. 1.

Fig. 3 is a section drawn to an enlarged scale on the line II—II of Fig. 2.

Fig. 4 is a section on the line III—III of Fig. 3.

Referring to Figs. 1 and 2 the generator comprises a receptacle 1 having rounded edges and provided with a bottom 2 and a perforated cover for receiving two cylinders 3 and 4, provided with bottoms. A horizontal partition 5, placed against the bottoms of the cylinders forms, with a bottom 2 of the generator, a chamber which is divided by a transverse partition 6 into two chambers 7 and 8. The chambers 7 and 8 are respectively in communication, by tubes 9 and 10 with the upper parts of the cylinders 3 and 4. Cocks 11 and 12, (see Fig. 1) place the chambers 7 and 8 respectively in

communication with the exterior. The cocks 11 and 12 are placed in communication with each other by means of a pipe in which is located a three-way cock, as illustrated in Fig. 1. This cock serves the purpose of establishing communication between the cocks 11 and 12 or between the holder and atmosphere, so that the generated gas may be permitted to collect in the holder or may be taken from the holder and used while the generator is cutting off from the holder. The cylinder 3 receives the bell 13 of the generator, and this bell is provided with a tube 14 in its right hand part.

The system of two pockets is shown on a larger scale in Figs. 3 and 4. One of the pockets, the pocket 16, is perforated, while the other pocket, on the contrary, constitutes a seal. These two pockets are secured to a rod 17 which passes through the upper part of the cover, and which is guided in a sleeve 18 fixed on the latter. By rotating the rod, the perforated pocket or the seal 15 is brought opposite to the tube 14. When the perforated pocket faces the tube 14, the part 15¹ of the seal comes into contact with the tube 14, thereby preventing upward displacement of the rod. Displacement downward is prevented by means of the plate 19, which can turn about an axis 20 on an extension of the rod 17. When the seal 15 faces the tube 14, the rod can be raised, the tube penetrating into the seal which is of larger diameter, and the system is held in this position by making the plate 19 rotate about the axis 20 in such a way that the straight part 21 of the plate 19 comes into contact with the cover, and occupies the position represented by dotted lines in Fig. 2. It is, of course, to be understood that the generator is of the dip type, where the carbid is immersed in the water. At the time of the introduction of the carbid the pipe 4 is in the water, and to prevent the escape of gas, the pocket 6 is rapidly rotated to close off the piston 14.

The operation is as follows:

The cylinder 3 is filled up to a certain level, the perforated pocket is brought opposite to tube 14, and the charge of carbid is introduced. All that is required then is to rotate the system through 180° and to move the rod up again. The carbid is in contact with the water, while the seal 15, which is full of water, forms a watertight joint be-

tween the tube 14 and the inside of the generator.

The gas generated collects in the top of the bell, and is led from there to the apparatus in which it is to be utilized by the tube 9, the chamber 7 and the cock 11. The apparatus may be provided with a holder, as shown in the constructional form described, the bell 22 forming the holder being introduced into the cylinder 4. This bell is provided at its upper part with a cross piece 23 and two screws 24 and 25, which may be clamped by jam nuts 26 and 27. The shanks of the screws 24 and 25 terminate in stops 28 and 29, and pass through holes in the generator cover. By suitably adjusting the position of the screws 24 and 25, the distance between the stops 28 and 29 and the generator cover, and consequently the maximum lift of the bell 22 can be varied. To work the bell-holder, a three-way cock is used, one of the passages being connected with the service apparatus, and the two others with the cocks 11 and 12.

To charge the bell-holder, communication is established between the passages connected to the cocks 11 and 12. The generator then fills the bell, and when the desired quantity of gas has been collected, and the bell-holder is at its maximum lift, the communication between the generator and the bell is cut off, and the bell-holder is connected to the service apparatus.

It is, of course, to be understood that the measuring device 22 is used when it is desired to measure or dispense a given quantity of gas so that when that quantity has been measured, communication between the generator and holder is destroyed. When it is not necessary to measure the gas communication between the holder and generator is also cut off, the gas escaping from the pipe 9.

The generator described may be modified, and the pockets may be of any suitable shape, and may be actuated in any manner in order to bring them opposite to the well.

Copies of this patent may be obtained for five cents each, by addressing the "Commissioner of Patents, Washington, D. C."

Having now particularly described and ascertained the nature of my said invention, and in what manner the same is to be performed, I declare that what I claim is:

1. An acetylene or like generator including a water container, a tube extending into the same, a pocket adapted to contain carbid, a pocket adapted to contain water, said pockets being capable of being alternately brought into registration with the bottom of the tube, and the water containing pocket being adapted to seal the lower end of the tube. 50

2. An acetylene or like generator including a container, a tube extending into the same, a pocket adapted to contain carbid, a pocket adapted to contain water, and a rod supporting said pockets, said rod being capable of rotatable and longitudinal movements whereby the pockets may be revolved and alternately brought into registration with the bottom of the tube, and the water containing pocket may be lifted to form a seal for the lower end of the tube. 60

3. An acetylene or like generator including a container, a tube extending into the same, a pocket adapted to contain carbid, a pocket adapted to contain water, a rod supporting said pockets, said rod being capable of rotatable and longitudinal movements whereby the pockets may be revolved and alternately brought into registration with the bottom of the tube and the water containing pocket may be lifted to form a seal for the lower end of the tube, and means for holding said rod in its lifted positions including a plate carried by the rod and resting flat on the cover of the container during the rotation of the pockets, said plate being adapted to be turned upwardly to displace the rod vertically. 75

In testimony whereof I affix my signature, in presence of two witnesses.

DEMETRIO MAGGIORA.
